United States Patent Office

Des. 184,933
Patented Apr. 21, 1959

184,933

DISH

Orville C. Hamon, Cedars, Okla.

Application July 8, 1958, Serial No. 51,702

Term of patent 14 years

(Cl. D36—2)

Figure 1 is a side elevational view of a dish, showing my new design;

Figure 2 is a top plan view; and

Figure 3 is an end elevational view looking from right of Figure 1.

I claim:

The ornamental design for a dish, as shown.
